[57] ABSTRACT

A display stand for rug samples or the like comprises a rotating wing having the lower end pivotally mounted on a base and the upper end pivotally mounted in one end of a horizontal arm. The arm is supported by an upright post, and the lower end of the post is somewhat loosely mounted in a tubular socket member which itself is part of a three-sided base support.

DISPLAY STAND

This invention relates to a display stand for displaying samples of carpets and the like.

We envisioned, during the course of conceiving the present invention, of a rectangular wing or panel, essentially of a large sheet of foraminous metal confined by a rigid frame and supported on a triangular base for swinging movement, the openings in the foraminous sheet accepting clips or hooks whereby a carpet sample could be hung thereby. As a matter of ornamental design, and in an effort to impart stability, it was envisioned that rigid posts should extend upward from the three corners of the base and rigidified at their upper ends by a triangular brace complementary with the base. Structure as thus conceived was built with the wing pivoted on hinge pins mounted in aligned openings formed in one of the sides of the base and in one of the sides of the top brace, but it was found that when the wing, with its burden of samples, was swung forcefully the structure would tend to tip and hence amounted to what is known in legal terminology as an attractive nuisance, tempting to children in the company of their parents in a department store or any other merchandising center where the display stand would be used.

Having discovered the unstable character of a display stand thus constructed we concerned ourselves with a structure which would not topple even though the attractiveness and stability of the triangular base should be retained. Accordingly an object of the present invention is to enable a swinging wing or panel of the aforesaid kind, supported in part by a triangular base, to be stabilized against toppling in spite of heavy rug samples that may be suspended thereon for display and to accomplish this object by extending a single post upward from the base, the post having an arm extended therefrom and the free or outer end of the arm providing a pivot point for the top of the wing. More specifically objects of the invention are to stabilize the base by three legs, one at each of the three corners of the base and one of the legs being presented by the lower end of an upright socket; the socket telescopically receives the lower end of the post, and the arm which affords the upper pivot point is flexible so that the wing may be conveniently related to the remaining structure in the manner hereinafter described.

Other and further objects of the present invention will be apparent from the following description and claims and are illustrated in the accompanying drawings which, by way of illustration, show a preferred embodiment of the present invention and the principle thereof and what we now consider to be the best mode in which we have contemplated applying that principle. Other embodiments of the invention embodying the same or equivalent principles may be used and structural changes may be made as desired by those skilled in the art without departing from the present invention.

In the drawings:

FIG. 1 is a front elevation of the display stand of the present invention;

FIG. 2 is a side elevation of the stand shown in FIG. 1 but with the wing turned 90°;

FIG. 3 is a perspective view of the stand;

FIGS. 4 and 5 are respectively front and side elevations of the supporting structure for the wing;

FIG. 6 is a front elevation of a support base;

FIG. 7 is a top plan view of the base shown in FIG. 6; and

FIG. 8 is a schematic view of the earlier structure found unsatisfactory.

The display stand 10, FIGS. 1, 2 and 3, comprises a revolving wing or panel 12 pivotally mounted on a support 15, the support 15 comprising a base 16 and an upright post 17 extending upwardly therefrom.

In FIG. 1 the wing 12 faces the observer and in FIG. 10 2 it has been turned 90°. It may be turned at any intermediate position, and in fact the present invention assumes that the wing 12 at times may be swung violently in a 360° arc.

15 The wing 12 comprises a rectangular frame 20 of molding strips such as disclosed in Best U.S. Pat. No. 3,351,211 tightly confining a sheet of tough foraminous metal 21 enabling rug samples or the like to be clipped thereto as by the clips disclosed in Best U.S. Pat. No. 3,195,733.

20 Referring to FIGS. 4 and 5 the base unit 16 is constructed in the form of an isosceles triangle, FIG. 7, consisting of a long base side 23 and two legs 24 and 25, each of square metal tubing.

25 As shown in FIG. 6, a pair of front legs 28 (square tubing) are rigidly attached to the opposed ends of the side 23 of base 16. The opposed ends of the tube 23 are squared off, and the front ends of the opposed side tubes 24 and 25 are cut at 45° angles to fit neatly against the back of side 23 to which they are affixed. The rear ends of the leg member 24 and 25 are squared off and fit neatly against adjacent sides of an upright, square socket member 30. The various parts of the base member thus described are preferably joined by welds.

30 The socket member 30, FIG. 6, is of vertical extent, and the lower end 31 thereof serves as a third leg so that the base may be stably supported on any planar surface.

35 The socket member 30 is also of square tubing so that the lower end of the post 17 may be telescopically set loosely therein as will be appreciated from what is shown in FIGS. 4 and 5. Thus, the upright post is of less cross-section than the opening in the socket so that there is a slight amount of free play. Screws as 33 are 40 passed through aligned openings in the socket and the lower end of the post 17 thereby to hold the post against displacement; nonetheless, the post is free to wobble a slight bit.

45 An arm 36 is welded to the top of the post to extend outward therefrom on a line normal to the span of side 23 of the base. The free or outer end of arm 36 is provided with an opening 37, and this opening is on a plumb line with a related opening 38 formed at the center of the span of the base tube 23.

50 The upper and lower cross members defining frame 20 are provided with hinge pins 39 and 40, FIG. 1. The lower hinge pin 40 is adapted to be set in the opening 38 with a thrust washer 41, FIG. 2, interposed between the frame of the wing and the upper surface of the base tube 23. A similar thrust washer 42, FIG. 2, is centered on the upper hinge pin 39. The clamping arm 36 may be easily flexed to allow its opening 37 to register with and accept the free end of the upper hinge pin.

55 The rug samples to be suspended by clamps or hooks anchored in the openings of the metal sheet 21 are relatively heavy as can be appreciated, and samples will be located on both sides of the wing which is to be rotated

in the course of the sales demonstration or as the customer himself may desire.

FIG. 8 is a schematic view of an earlier structure which was found to be unstable in exhibiting a tendency to tip when the wing, bearing rug samples, was turned rapidly. This tendency to tip is not exhibited by the display stand shown in FIGS. 1 through 7, and in fact the wing or panel 20, heavily burdened with rug samples, may be rotated as rapidly as possible by hand and yet the stand remains steady in all respects. Very likely the lack of absolute rigidity between the post 17 and the supporting base plays a role in that the upper end thereof displays a slight amount of precession or eccentricity about the longitudinal axis of the post when the heavy wing is swung rapidly, a phenomenon 15 not possible with the earlier attempt, FIG. 8.

We claim:

1. A display stand for samples of carpets and the like comprising a triangular base with at least two equal sides and three dependent legs of substantially equal length, one leg at each corner of the base, an upright post secured to the corner of the base between the two

equal sides, an arm extended horizontally outward from the top of the post, and a rectangular wing for supporting such samples, the top of the wing being pivotally attached to the outer end of the arm and the bottom of the wing being pivotally attached to substantially the longitudinal center of the side of the base opposite the corner to which the upright post is secured.

2. A stand according to claim 1 wherein one of the legs is the lower end of a tubular socket member, and the lower end of the post being loosely supported within the socket member, whereby the post will undergo precession about its longitudinal axis when the wing supporting carpet samples is swung.

3. A stand according to claim 2 wherein the wing has a hinge pin at its top and a hinge pin at its bottom, the bottom hinge pin fitting in an opening in one of the sides of the base and the top hinge pin fitting in an opening at the outer end of said arm, said arm being flexible so that it may be raised when registering the top hinge pin to the opening in said arm.
